DESIGN FOR AN ESCUTCHEON PLATE FOR STOVES OR THE LIKE

Elmer D. Pellegrin, Woodstock, Ill., assignor to
Geo. D. Roper Corporation, Rockford, Ill., a
corporation of Illinois

Application March 24, 1941, Serial No. 99,801

Term of patent 7 years

To all whom it may concern:

Be it known that I, Elmer D. Pellegrin, a citizen of the United States, residing at Woodstock, in the county of McHenry and State of Illinois, have invented a new, original, and ornamental Design for an Escutcheon Plate for Stoves or the like, of which the following is a specification, reference being had to the accompanying drawing, forming part thereof.

In the drawing:

Fig. 1 is a front elevational view of an escutcheon plate for stoves or the like showing my new design;

Fig. 2 is a top plan view thereof, and

Fig. 3 is an end elevational view thereof.

I claim:

The ornamental design for an escutcheon plate for stoves or the like, substantially as shown.

ELMER D. PELLEGRIN.
